By her attorney, Robert M. Wright

UNITED STATES PATENT OFFICE.

LURA S. BRAINERD, OF MERIDEN, CONNECTICUT.

METHOD OF MAKING MOTION-PICTURES.

1,296,471.

Specification of Letters Patent.

Patented Mar. 4, 1919.

Application filed January 18, 1915. Serial No. 2,894.

To all whom it may concern:

Be it known that I, LURA S. BRAINERD, a citizen of the United States of America, residing at Meriden in the county of New Haven and State of Connecticut, have invented a new and useful Improvement in Methods of Making Motion-Pictures, of which the following is a specification.

This invention relates to a continuous method of producing a theatrical performance which involves and includes the depicting of cartoons in quick succession, in which the movements of human figures are imitated and simulated, displaying such representations in seemingly impossible positions, and then by a continuity of movement and action carrying on the theme and story by moving picture actors.

In this manner and by this method, I effect a joinder of these two phases of production and bring about a connected and complex story by interweaving each other.

The order and relationship can be changed and the first part of the story can be told by moving pictures taken from living actors and can be taken up at the proper time and place by the cartoons; in carrying my invention into practical effect, I produce surprising and amusing results.

I will proceed to describe one method of carrying my invention into effect and in order to render the explanation clear and plain, I will explain it in connection with the accompanying drawings which form a part of this specification and in which—

Figure 1 shows means and instrumentalities employed by me for securing the desired film from which the final picture is projected on the screen for exhibition purposes; this is a perspective view and embraces the camera and various essential properties and apparatus.

Fig. 2, is a vertical section to a larger scale of the apparatus employed by me for securing the different phases of display and transferring them to the single continuous film, as will be more fully explained.

Fig. 3, is a detail view of a clutch employed for carrying my invention into effect.

Fig. 4, discloses the manner of feeding the cartoons past the camera shutter in the act and process of being photographed upon the continuous negative film.

Fig. 5, illustrates the resultant film show-

ing how the story of the play or drama is bridged across from one phase of display to the other and disclosing a continuous and artistic development whereby the final display upon the screen will be rendered effective and the illusion sustained. 60

In these drawings A represents a camera similar to those employed in taking moving picture films; for this reason I need not explain it in detail as its construction and 65 method of operation is well known in the art; the lens and the details immediate thereto is shown at B; a shutter at C.

The film is shown at D; this film is mounted upon and its movements are controlled by the regular unwinding and winding up apparatus E and F as now generally employed and whose details I need not particularly explain; but I will here say that I make only such changes in the regular 75 commercial apparatus as is necessary to carry my invention into effect.

Referring to Fig. 1 at G, I show a scene which the camera is taking as a part of a moving picture drama. At H is shown 80 a living moving picture actor sitting at a sewing machine J. At K is a dummy figure and at L, M, N are implements of the dressmaker's art. O is a window disclosing scenery beyond. At P is a movable 85 frame having a square opening Q and immediately behind this is the camera A.

The camera receives the light reflected from the scene G through the opening Q and I utilize this same space to place the cartoons R when the latter are to be substituted for the real images and objects. 90

The cartoon carrier is shown at r in Fig. 4 and in operating position in Fig. 2; the carrier may be operated by means of the 95 lever S pivoted at s in a sliding block s¹ and having finger s² registering with the openings in the cartoon carrier and pulling it down by the rotation of the arm s³ to which it is pivoted this latter being mounted on the drum s⁴ and receiving its motion through chain s⁵ from the drum T. The drum T rotates on center T¹ in direction of arrow and carries corresponding arm t to lever t¹ the latter pivoted at t² to sliding block t³ having finger t⁴ which latter is adapted to enter the registering openings in the film D. The center T¹ is provided with clutch member U intermeshing with clutch member U¹ governed by lever U². 100 105 110

- In carrying out my invention and method and reducing it to a commercial proposition, it may be modified in various ways and the order of employment may be shifted so as to bring the cartoon display only at the end; or it may be at both ends as explained; in other displays the cartoons may be introduced at one or more intermediate points, the object always being to maintain such a similarity in the position and appearance of the persons or objects photographed as to create in the mind of the spectator the impression of continuity of movement and images. Amusing and seemingly impossible situations can be developed in this manner, but the similarity of the images depicted and the artistic method of merging them will lend sufficient realism to create the desired dramatic effect.
- 20 Previous to the taking of pictures, the operator can remove the slide V and by means of the lever V^1 gear V^2 and rack V^4 move the lens B so that the moving scene will be focused upon the ground glass W , or that the cartoons will be so focused. Stop pins W^1 can be so placed on a dial plate W^2 that the movements of the lever V^1 will be checked when moved to the position to cause said change of focus.
- 25 30 If desired also, removable cartoon cards shown by dotted line R in Fig. 2 can be placed in the receptacle X , thereby avoiding the necessity of moving the cartoon carrier R .
- 35 Having thus described my invention, the following is what I claim as new and useful therein and desire to secure by Letters Patent:
1. The method of producing motion picture films that consist in placing animate objects and pictures of inanimate objects successively in the same line of reflection to a moving picture camera in operation, and one picture after another in front of the camera whereby the pictures of the inanimate objects and of the animate objects one

following the other are produced in the same field upon the film in the camera.

2. The method of making motion picture films that consists in producing a movement 50 of pictures of inanimate objects in rapid succession in the same line of reflection with animate objects before a moving picture camera in operation, and in obscuring one set of said objects from the camera when 55 the other set of said objects is reflected thereon.

3. The method of making a moving picture film that consists in moving cartoon pictures in rapid succession between a camera and a stage setting including living actors, and in removing the cartoons from the range of the camera while continuing the 60 operation of the latter to produce pictures from said stage setting.

4. The method of making moving picture films that consists in producing separately but along the same line of reflection to a moving picture camera, pictures of animate objects, and successive pictures of cartoons 70 of inanimate objects.

5. The method of producing motion picture films that consists in placing animate objects and pictures movably operated of inanimate objects successively in the same 75 line of reflection to a moving picture camera in substantially continuous operation, and in producing a movement of such pictures in rapid succession in front of the camera whereby the pictures of the inanimate objects and the animate objects, one following the other are produced in the same field upon the film in the camera.

In testimony whereof, I have signed my name to this specification in the presence 85 of two subscribing witnesses, this 5th day of January, 1915.

LURA S. BRAINERD.
